ELECTRIC CABLE AND APPARATUS FOR
MANUFACTURING IT

Helmer J. Boe, Maplewood, N. J., assignor to Western Electric Company, Incorporated, New York, N. Y., a corporation of New York

Application June 30, 1932, Serial No. 620,120

10 Claims. (Cl. 173—265)

This invention relates to an electric conducting system and apparatus for making it, and more particularly to a concentric conductor system for transmitting with small attenuation a band of frequencies whose upper limit extends well above the frequencies now employed in carrier transmission.

It has been proposed in one instance to manufacture a concentric conductor system by employing a spiral insulating arrangement comprising a series of spokes passed transversely through the inner conductor and arranged spirally along the inner conductor with their outer ends acting as supports for the outer conductor for insulating the two conductors from each other, and in other instances to employ concentric conductors each formed of tubing or into the general shape of the metallic tape employed for protecting the so-called B. X. cable and separated from each other by spaced washers or a formed strip of generally helical configuration.

Objects of the invention are to provide an improved coaxial conductor system for high frequency transmission and apparatus for forming the conductor system in which one of the conductors acts as a return for the other.

According to one embodiment of the invention herein shown and described the coaxial conductor pair have a substantially air dielectric therebetween, the inner conductor has slotted washers of insulating material spaced thereon, with the radial direction of the slots in successive washers rotating about the inner conductor, and which grip the inner conductor firmly and the outer conductor encloses the inner conductor and is supported by the washers.

The invention may be better understood by reference to the following detailed description and accompanying drawings, in which—

Fig. 1 is a transverse sectional view of a group of conducting systems in accordance with one embodiment of the invention arranged in the form of a cable;

Fig. 2 is a plan view of one of the insulating discs employed in the conducting systems;

Fig. 3 is a transverse sectional view of a group of conducting systems in accordance with another embodiment of the invention arranged in the form of a cable;

Fig. 4 is a perspective view of a portion of one of the conducting systems shown in Fig. 1;

Fig. 5 is a perspective view of a portion of one of the conducting systems shown in Fig. 3;

Fig. 6 is a section on the line 6—6 of Fig. 7;

Fig. 7 is a view in side elevation, partially in

cross-section, of an apparatus for constructing the conducting systems shown in Figs. 1 and 4;

Fig. 8 is a vertical sectional view on the line 8—8 of Fig. 7, and

Fig. 9 is a view in side elevation, partially in cross-section, of an apparatus for constructing the conducting systems shown in Figs. 3 and 5.

In a preferred embodiment of a conducting system, as shown in Figs. 1, 2 and 4, each of the concentric conductor systems 10 comprises an inner conductor 11, a plurality of slotted discs or washers 20 of elastically deformable insulating material assembled over the inner conductor 11 so that each disc grips the inner conductor 11 firmly, with the discs in widely spaced relation and with the radial direction of the slots 21 rotating about the inner conductor 11. Around the spaced insulating discs 20 is assembled an enclosing outer conductor preferably comprising a plurality of wavy conducting wires 13 held in place by suitable binding means 44 to form a cylinder having the same axis as the central conductor. A plurality of the concentric conductor systems 10 are assembled together and held in place by suitable binding means 16 over which is applied an outer protective covering 17 which may comprise a sheath of lead extruded over the assembled group, or rubber, gutta percha or other suitable material continuously applied over the assembled group.

In order that the attenuation may be made small at high frequencies, the leakage loss between the conductors must be as small as possible. As the leakage loss is due to the dielectric interposed between the conductors the principal volume constituent of the dielectric should be air since air produces no leakage loss. Accordingly, the spaced insulating washers 20 which maintain the inner conductor 11 and the wavy wires 13, comprising the outer conductor, in concentric relation and out of electrical contact with each other should be separated from each other by suitable distances and should be made as thin as possible consistent with required mechanical strength. They are composed of material having a small loss angle and low dielectric constant in order to make the leakage loss as small as possible. The insulating discs or washers 20 are constructed as shown in Fig. 2 with a circular hole therein of a size such that the washer will firmly grip the inner conductor 11 and a slot 21 slightly narrower than the diameter of the circular hole. With this construction the washer 20, after having been sprung into place over the inner conductor 11, cannot be readily

displaced therefrom. Hence the washers are made of an elastically deformable insulating material, in order to be sprung over the inner conductor and to grip it elastically and firmly.

5 In a preferred embodiment of apparatus as shown in Figs. 6, 7 and 8, for forming the concentric conducting system shown in Figs. 1 and 4, a supply reel 50 containing a length of inner conductor 11 is mounted on a supporting bracket 10 51. A mechanism 52 (Figs. 7 and 8) is provided for applying the insulating discs or washers 20 intermittently at predetermined intervals on the inner conductor 11 so that the discs 20 grip the conductor 11 firmly and the radial directions of 15 successive slots 21 rotate about the conductor 11.

In the embodiment illustrated in Fig. 8 the discs 20 are applied with the slots extending in three different directions although it is also within the scope of the invention to have the 20 slots extending in two or in more than three different directions. Three individual supply means or magazines 53, 54 and 55, each containing a supply of discs 20, are arranged about the inner conductor 11. Each of the supply means is 25 arranged so that the discs will be forced toward an opening 56 therein and each has a spring controlled plunger 57 for forcing the discs 20 into position on the wire 11. A cam arrangement 58 is provided to force the plunger 57 toward the 30 wire 11 against the tension of the springs 59. The cam arrangement 58 is arranged to rotate so that the discs 20 are ejected from the supply means 53, 54 and 55 in succession. A plurality of supplies 60 of conducting wires 13 are mounted 35 on a suitable support 61. A distributing plate 62 (Figs. 6 and 7) having an aperture 63 through which the conductor 11, with the discs 20 assembled thereon is adapted to pass and a plurality of apertures 64 preferably arranged around 40 the aperture 63 and through which the wires 13 are adapted to pass is rotatably mounted in a support 65. A crank 66 attached to a gear 67 and a connecting rod 68 attached to the crank 66 and to the distributing plate 62 are provided 45 to give an oscillating movement to the distributing plate 62 when the gear 67 is rotated. A sizing die or polisher 69 is provided having a cone shaped opening 70 at one end to properly assemble the wires 13 over the insulating discs 50 20. The serving head 71 having a rotating binder supply 72 carrying a supply of binders 44 is provided to suitably bind the inner and outer conductors with their associated discs.

A capstan 73 is provided to pull the inner conductor, the wires forming the outer conductor, and the assembled conducting system through the apparatus after which it may be accumulated on a take-up reel 74.

A suitable source of power such as a motor 60 75, and suitable connecting transmission elements are provided to drive the cam 58 for applying the discs to the inner conductor, the gears 65 67 for oscillating the distributing plate 62, the supply means 72 around the concentric conducting system, the capstan 73 and the take-up reel 74.

The operation of the system shown in Figs. 6, 7 and 8 is as follows: As the motor 75 rotates the capstan 73 and the take-up reel 74, the inner conductor 11 is drawn from the supply reel 50 and the wires 13 are drawn from the supplies 60 through the apparatus. As the inner conductor 11 is drawn through the mechanism 52, the cam 58 rotates and forces the discs 20 70 from the supply means 53, 54 and 55, in suc-

cession. As the conductor 11 with the discs 20 assembled thereon, and the wires 13, are drawn through the distributing plate 62 and the sizing die 69, the oscillating movement of the distributing plate 62 continuously changes the radial position of each of the wires 13 with respect to the inner conductor 11 which produces a wavy condition in the wires 13 as shown in Fig. 4. As the concentric conductor system passes through the remainder of the apparatus the 10 rotation of the binder supply 72 applies the binder 44 and the assembled conducting system is wound onto the take-up reel 74.

In another preferred embodiment of a conducting system, as shown in Figs. 3 and 5, the inner conductor 31 of each of the concentric conducting systems may comprise a cylindrical tube of a material easily flexed, such as lead tubing over which a coating of a suitable good conducting material such as copper or silver has 20 been applied by electroplating or other suitable methods and the outer conductor 33 may comprise a cylindrical tube formed from a sheet or tape of material easily flexed such as lead and having a coating of a suitable conducting material such as copper or silver applied to the inner surface by electroplating or other suitable methods. The edges 34 of the sheet forming the outer conductor are arranged to abut and are secured together by soldering, brazing or other 30 suitable methods to form a water-tight outer conductor. The insulating discs 20 are arranged as described above in connection with the conducting system shown in Figs. 1 and 4.

Referring to Fig. 9 a preferred embodiment of 35 apparatus for forming the concentric conducting system 30 shown in Figs. 3 and 5 is in general similar to that shown in Fig. 7. The supply reel 50 carrying a supply of inner conductor 31, the mechanism 52 for applying the insulating discs 20 40 on the inner conductor 31 and the take-up reel 74 on which the concentric conducting system 30 is accumulated are the same as corresponding parts shown in Fig. 7.

A supply reel 80 containing a length of tape 45 from which the outer conductor is formed is mounted beneath the inner conductor 31 with its associated discs 20. A forming roller 81 having a half round peripheral groove therein is positioned so that the inner conductor 31 and the discs 20 50 assembled thereon are forced against the central portion of the tape to form or curve the bottom or central portion thereof. Two sets of forming rollers and associated guides 82-83 and 84-85 55 are provided with half round peripheral grooves 50 therein to form the sides of the tape comprising the outer conductor 33 around the insulating discs 20.

A suitable mechanism 86 is provided to join the edges 34 of the outer conductor. The mechanism 86 may take the form of suitable soldering, 60 brazing or welding apparatus to unite the edges 34 to form a water-tight joint. A capstan 87, preferably of the so-called endless belt or tractor type is provided to pull the inner conductor 31, 65 the outer conductor 33 and the assembled conducting system 30 through the apparatus. Suitable transmission elements are employed to connect the power source 75 with the mechanism 52, the capstan 87 and the take-up reel 74.

The operation of the system shown in Fig. 9 is as follows:

As the motor 75 drives the capstan 87 and the take-up reel 74, the inner conductor 31 is drawn from the supply reel 50 and the tape forming the 75

outer conductor 33 is drawn from the supply reel 80 through the apparatus. As the inner conductor 31 is drawn through the mechanism 52 the discs 20 are assembled thereon as described above 5 in connection with Fig. 7. As the conductor 31 with the discs 20 assembled thereon and the tape from the supply reel 80 which forms the outer conductor 33 are drawn through the forming apparatus 81, 82, 83, 84 and 85, the tape is formed 10 around the inner conductor and insulating discs and takes the form shown in Figs. 3 and 5. As the conducting system is drawn through the apparatus 86 the edges 34 are heated, melted and subsequently upon solidification fuse together to 15 form a water-tight joint.

It is to be understood that the invention is not to be limited to the particular embodiment shown, nor to the particular arrangements that have been described and shown in detail but only 20 by the scope of the appended claims.

What is claimed is:

1. A coaxial conductor pair having air as the 25 principal volume constituent of the dielectric between the conductors, comprising an inner conductor, a plurality of thin discs of elastically deformable insulating material and each having a radial slot therein and elastically gripping the inner conductor between the walls of such slot to resist longitudinal displacement on the conductor, 30 the radial slots of successive washers extending out from the inner conductor in different directions and the discs being widely spaced along the inner conductor, and an enveloping outer conductor applied over the outer edges of the discs and thereby spaced coaxially from the inner conductor.

2. In an apparatus for making a flexible concentric conductor having a dielectric which is 40 substantially air, means for continually advancing an inner conductor, means for automatically pressing onto said inner conductor at predetermined intervals from different radial directions, slotted insulating discs having a central hole so that the discs grip the inner conductor firmly, 45 the sides of the holes in the discs are perpendicular to the inner conductor and the slots in successive discs extend at different radial directions from the inner conductor, and means for assembling an outer conductor comprising a plurality 50 of conducting elements parallel to each other around and in contact with the spaced insulating discs, comprising a rotatably mounted distributing plate having an aperture through which the inner conductor and the assembled discs is 55 adapted to pass and a plurality of apertures through which the conducting elements forming the outer conductor are adapted to pass, and means for oscillating said distributing plate.

3. In an apparatus for making a coaxial conductor pair having air as the principal volume constituent of the dielectric between the conductors, means to continually advance an inner conductor, means to spring radially slotted thin discs of elastically deformable insulating material 60 over the inner conductor at widely spaced intervals along the conductor to grip the conductor between the walls of the slots to resist longitudinal displacement of the discs on the conductor, the discs being sprung over the conductor in successive 65 different radial directions thereto whereby successive discs stand on the conductor with the radial slots of the discs extending from the conductor in different directions, and means to continuously longitudinally wave and apply a plurality 70 of wires over the outer edges of the discs to form an outer conductor coaxially spaced from the inner conductor by the discs.

4. In an apparatus for making a flexible concentric conductor pair having air as the principal volume constituent of the dielectric between the conductors, means for continuously advancing an inner conductor, means to place radially slotted thin discs of elastically deformable insulating material intermittently on the inner conductor at widely spaced intervals along the conductor, and means to apply an outer coaxial conductor over the outer edges of the discs, the said means to set the discs on the inner conductor comprising a plurality of stationary magazines 10 radially disposed around the advancing conductor and adapted to present successive discs to the conductor from successively differing directions and with the radial slots of the discs directed toward the conductor, and means to push and 15 thereby spring the successive discs over the conductor to stand thereon perpendicularly thereto with the radial slots of successive discs extending from the conductor in different directions and with the conductor firmly gripped 20 between the walls of the slots.

5. In an apparatus for making electrical conductors, means for continually advancing a conductor, and means for placing radially slotted discs on the conductor comprising a plurality of 30 magazines arranged in different radial directions around the conductor and each having means to present discs successively to the conductor, and means to press the discs thus presented into position on the conductor with the conductor 35 between the walls of the slots in the discs.

6. In an apparatus for making electrical conductors, means for continually advancing a conductor, and means for placing radially slotted discs on the conductor comprising a plurality of 40 magazines arranged in different radial directions around the conductor and each having means to present discs successively to the conductor, and means to press the discs thus presented into position on the conductor with the conductor 45 between the walls of the slots in the discs, the last named means including a plunger in each magazine and a rotating cam to operate the plungers in succession.

7. In an apparatus for making a coaxial conductor pair having air as the principal volume constituent of the dielectric between the conductors, means to advance an inner conductor, means to spring radially slotted thin discs of 50 elastically deformable insulating material over the inner conductor at widely spaced intervals along the conductor to grip the conductor between the walls of the slots to resist longitudinal displacement of the discs on the conductor, the discs being sprung over the conductor in successive 55 different radial directions thereto whereby successive discs stand on the conductor with the radial slots of the discs extending from the conductor in different directions, and means to longitudinally wave and apply a plurality of 60 wires over the outer edges of the discs to form an outer conductor coaxially spaced from the inner conductor by the discs.

8. In an apparatus for making a flexible concentric conductor pair having air as the principal volume constituent of the dielectric between the conductors, means for advancing an inner conductor, means to place radially slotted thin discs of elastically deformable insulating material intermittently on the inner conductor at 70

- widely spaced intervals along the conductor, and means to apply an outer coaxial conductor over the outer edges of the discs, the said means to set the discs on the inner conductor comprising a plurality of stationary magazines radially disposed around the advancing conductor and adapted to present successive discs to the conductor from successively differing directions and with the radial slots of the discs directed toward the conductor, and means to push and thereby spring the successive discs over the conductor to stand thereon perpendicularly thereto with the radial slots of successive discs extending from the conductor in different directions and with the conductor firmly gripped between the walls of the slots.
9. In an apparatus for making electrical conductors, means for advancing a conductor, and means for placing radially slotted discs on the conductor comprising a plurality of magazines

arranged in different radial directions around the conductor and each having means to present discs successively to the conductor, and means to press the discs thus presented into position on the conductor with the conductor between the walls of the slots in the discs.

10. In an apparatus for making electrical conductors, means for advancing a conductor, and means for placing radially slotted discs on the conductor comprising a plurality of magazines arranged in different radial directions around the conductor and each having means to present discs successively to the conductor, and means to press the discs thus presented into position on the conductor with the conductor between the walls of the slots in the discs, the last named means including a plunger in each magazine and a rotating cam to operate the plungers in succession.
